(57) **CLAIM**

The ornamental design for a watering spike as shown and described.

DESCRIPTION

FIG. 1 is a top perspective view of a watering spike according to our new design;

FIG. 2 is another top perspective view thereof;

FIG. 3 is a bottom perspective view thereof;

FIG. 4 is another bottom perspective view thereof;

FIG. 5 is a front elevation thereof;

FIG. 6 is a rear elevation thereof;

FIG. 7 is a left-side elevation view thereof;

FIG. 8 is a right-side elevation view thereof;

FIG. 9 is a top view thereof; and,

FIG. 10 is a bottom view thereof.

Conventional shading is illustrated for purposes of highlighting the line drawing, but forms no part of the claimed design.

1 Claim, 10 Drawing Sheets
